United States Patent Office.

EMELINE T. ANNIS, OF MOUNT MORRIS, NEW YORK.

Design No. 4,501, dated December 6, 1870.

DESIGN FOR A LAMP-CHIMNEY CLEANER.

The Schedule referred to in these Letters Patent and making part of the same.

To all whom it may concern:

Be it known that I, EMELINE T. ANNIS, of Mount Morris, in the county of Livingston and State of New York, have invented a new and original Design for Lamp-Chimney Cleaner; and I do hereby declare that the following is a full, clear, and exact description thereof, which will enable others skilled in the art to make and use the same, reference being had to the accompanying drawing forming part of this specification.

The nature of my invention is fully represented in the accompanying drawing, to which reference is made.

I claim as my invention—

The design for a lamp-chimney cleaner, as shown.
EMELINE T. ANNIS.
